CLAIM

The ornamental design for a tray for the growing of seedlings, as shown and described.

DESCRIPTION

FIG. 1 is a perspective view of a tray for the growing of seedlings showing my new design;

FIG. 2 is an enlarged rear elevation thereof, the front elevation being identical;

FIG. 3 is an enlarged left side elevation thereof, the right side elevation being identical;

FIG. 4 is a further enlarged fragmentary section taken in the direction of the arrows on line IV—IV of FIG. 5; and,

FIG. 5 is an enlarged bottom plan view thereof.
